(57) CLAIM

We claim the ornamental design for a lottery ticket dispenser, as shown and described.

DESCRIPTION

FIG. 1 is a front perspective view of a lottery ticket dispenser according to our new design.

FIG. 2 is a front elevation view thereof;

FIG. 3 is another front elevation view thereof;

FIG. 4 is an enlarged view showing the claimed features in isolation for clarity;

FIG. 5 is a right side elevation view thereof; and,

FIG. 6 is a top plan view thereof.

The broken lines in the drawings are for illustrative purposes only and form no part of the claimed design.
